UNITED STATES PATENT OFFICE.

MAURICE JAE TOPP, OF NEW YORK, N. Y.

COLLAR-SUPPORT.

18

No. 891,113.

Specification of Letters Patent.

Patented June 16, 1908.

Application filed December 17, 1907. Serial No. 406,862.

To all whom it may concern:

Be it known that I, MAURICE JAE TOPP, a citizen of the United States, and a resident of the city of New York, borough of Manhattan, in the county and State of New York, have invented a new and Improved Collar-Support, of which the following is a full, clear, and exact description.

My invention relates to collar supports and the like, my more particular object being to produce a type of stay for the purpose of stiffening the collar.

My invention further relates to means whereby the stay is rendered more easily extensible.

Reference is to be had to the accompanying drawings forming a part of this specification, in which similar characters of reference indicate corresponding parts in all the figures.

Figure 1 is a fragmentary elevation showing a portion of a lady's collar provided with one of the improved stays, and showing further the composite construction of the stay, whereby it may be shortened or elongated as desired; Fig. 2 is an enlarged central section through the stay, showing both members and the manner in which they are fitted together so as to render the stay extensible; Fig. 3 is an enlarged plan view showing the two members of the stay as partially separated, and further showing the means whereby these members may be detachably connected together, and adjusted relatively to each other for the purpose of regulating the length of the stay; and Fig. 4 is an enlarged vertical section through a collar equipped with my improved stay, this view further showing a jacket or envelop encircling and sewed directly to the collar.

The collar is shown at 5 and is provided with an edge 6 of lace. At 7 is shown a strip of metal provided at one of its ends with a tongue 8 made integral therewith and bent back upon the strip 7, as indicated more particularly in Fig. 3. This tongue is provided with a boss 9 made preferably by simply indenting the tongue 8 at or adjacent to the center thereof. The strip 7 is provided with a hole 10 spaced equidistant, and also with a hole 11, the latter being in registry with the boss 9. Another strip 12 is provided with holes 13 spaced equidistant, and is further provided with a tongue 14. This tongue is

adapted to pass through any one of the 55 holes 10 of the strip 7. The strips 7 and 12 are provided with holes 15 and 17 and are secured directly to the collar 5 by threads 18, as will be understood from Fig. 1.

In Fig. 4 the collar is shown at 19, and is 60 provided at 20 with a jacket used for holding the stay. This jacket is of substantially cylindrical form and is bent over at 21, 21^a, and its ends 22, 23 are secured directly to the collar 5 by the aid of threads 24. The edge 65 25 is secured to the collar in the usual manner.

Referring more particularly to Figs. 2 and 3, the operation of the device may be clearly understood. The operator grasps the strip 70 12 in the hand and inserts the tongue 14 through one of the holes 10 in the strip 7; the body of the strip 12 is next forced under the tongue 8 so that the boss 9 snaps into the hole 13. This holds the two strips in proper 75 relative position. The total aggregate length of the two strips is the length of the stay, and this may be controlled at will.

Where the device is used in connection with the jacket 20 as indicated in Fig. 4, the 80 length of the stay is governed as above described, with the exception, however, that the length of the stay is adjusted before the stay is inclosed within the jacket.

The strips 7 and 12 are preferably made by 85 stamping, the tongue 8 being left upon the strip 7 and bent over as indicated, so that the free edge of the tongue is a little short of one edge of the strip. The boss 9 being rounded as indicated in Fig. 2, enables the 90 strip 12 to be placed in proper position with comparative ease. For this purpose the strip 12 is merely slipped sidewise until the parts are in proper engagement.

Having thus described my invention, I 95 claim as new and desire to secure by Letters Patent,—

1. A stay comprising two strips, both having holes, one strip having a tongue for fitting the holes of the other strip, and said other strip having a spring tongue partially encompassing the companion strip, the said last-mentioned strip being provided with a boss for entering the holes of the other strip. 100

2. A stay comprising two strips of sheet 105 material, both provided with holes, one strip being provided with a tongue for entering the holes in the other strip, said other

strip being provided with a spring tongue partially encircling its companion strip, and further provided with a boss disposed centrally of said last-mentioned tongue and 5 made by indenting the same for the purpose of entering some one of the holes of the other strip.

In testimony whereof I have signed my name to this specification in the presence of two subscribing witnesses.

MAURICE JAE TOPP.
